(57) **CLAIM**

The ornamental design for a docking station for cell phone, as shown and described.

DESCRIPTION

FIG. 1 is a perspective view of docking station for cell phone showing my present design,
FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the docking station for cell phone with the supporter shown in a different position;

FIG. 9 is a perspective view of the docking station for cell phone showing a cell phone places on the supporter of FIG. 8; and,

FIG. 10 is a perspective view of the docking station for cell phone showing a cell phone rests with the present design.

The broken lines shown in the drawings are for the purpose of illustration only and form no part of the claimed design.
